UNITED STATES PATENT OFFICE.

FAY O. FARWELL, OF DUBUQUE, IOWA, ASSIGNOR OF ONE-HALF TO THE ADAMS COMPANY, OF SAME PLACE.

DESIGN FOR A HOT-AIR-REGISTER PLATE.

SPECIFICATION forming part of Design No. 27,606, dated August 31, 1897.

Application filed July 19, 1897. Serial No. 645,175. Term of patent 14 years.

To all whom it may concern:

Be it known that I, FAY O. FARWELL, a citizen of the United States, residing at Dubuque, in the county of Dubuque and State 5 of Iowa, have invented a certain new and original Design for Hot-Air-Register Plates; and I do hereby declare the following to be a full, clear, and close description thereof.

My invention has relation to a new and 10 original design for floor-plates for hot-air registers; and it essentially consists in a circular decorated register-plate secured to the floor, through which the stovepipe passes, all of which will be fully described in the following specification and illustrated in the accompanying drawing.

The figure is a plan view of my design.

Referring to the drawing, A designates the 15 register-plate. It is cast with a rim B around the outside, which rests upon the floor. Upon the upper surface of the rim B are one or more circular ribs *a* near its outer edge and one or more circular ribs *b*, set at a short distance from the ribs *a*. Around the pipe-hole

C is a flange D, which is provided with ob- 25 long holes *d*.

Between the rim B and the flange D is a circular movable plate II, provided with openings *h*. This plate II has a vine-and-leaf decoration K running around on its upper 30 surface and also across the openings *h*. The rim B and the flange D are connected together by strips (not shown) cast integral therewith, and upon which the circular plate II rests or is moved to close or open the register. 35

A register constructed in this manner and design is both useful and ornamental.

Having now described my design, what I claim, and desire to secure by Letters Patent, 40 is—

A design for hot-air-register plates as described and shown in the drawing.

In testimony whereof I affix my signature in the presence of two witnesses.

FAY O. FARWELL.
